UNITED STATES PATENT OFFICE.

AUGUST H. TOENS, OF INDIANAPOLIS, INDIANA.

REFRIGERATOR-CAR.

1,030,944.

Specification of Letters Patent.

Patented July 2, 1912.

Application filed September 14, 1911. Serial No. 649,248.

To all whom it may concern:

Be it known that I, AUGUST H. TOENS, a citizen of the United States, residing at Indianapolis, in the county of Marion and State of Indiana, have invented a new and useful Refrigerator-Car, of which the following is a specification, reference being had to the accompanying drawings and to the letters and figures of reference marked thereon.

This invention relates to railway car bodies that may be required to carry ice for keeping the contents of the car cool, the invention having reference more particularly to car construction that is designed to prevent deterioration of the car frame that might be due to the presence of water resulting from melting ice.

The object of the invention is to provide an improved refrigerator car body that will be adapted to carry ice, either as freight or for the purpose of refrigeration without detriment to the car; a further object being to provide a car of the above mentioned character that will be adapted to carry ice and not permit the ice water to come in contact with the framing of the car body, more especially for the protection of metallic framing, a still further object being to provide improved floor and side wall construction for refrigerator cars that shall be effective for the purpose intended, and be durable and economical in use.

The above mentioned and minor objects of the invention are attained in the construction illustrated in the accompanying drawings and herein fully described.

The invention consists also in the parts and combinations and arrangements of parts, as hereinafter particularly described and pointed out in the accompanying claims.

Referring to the drawings, Figure 1 is a longitudinal vertical sectional view centrally of the body of the car, constructed substantially in accordance with the invention; Fig. 2, a transverse sectional view on the line A A in Fig. 1; Fig. 3, a fragmentary section on the plane of the line B B in Fig. 1; Fig. 4, a horizontal section on the plane of the line C C in Fig. 1; Fig. 5, a fragmentary section on the plane of the line D D in Fig. 1 omitting portions of the structure; Fig. 6, a fragmentary central section, being a portion of Fig. 1 on an enlarged scale; and Fig. 7, a fragmentary vertical section on the plane of the line E E in Fig.

4 partially broken away to expose the wall foundation.

Similar reference characters in the several figures of the drawings indicate corresponding elements or features of construction herein referred to.

In practically carrying out the objects of the invention the framing of the car body may be varied in detail, the body preferably comprising two body-bolsters 1 and 2 on which are secured a suitable number of sills, there preferably being two side sills 3 and 4, two center sills 5 and 6 and two intermediate sills 7 and 8. The side sills preferably are composed of channel-iron beams or similar steel beams, arranged with the flanges thereof extending inwardly. The center sills and the intermediate sills preferably are composed of I-section iron or steel. Two end sills 9 and 10 are secured to the opposite ends of the longitudinally arranged sills. When metallic side sills and end sills are employed the sills 3 and 4 preferably comprise wooden upper portions 3' and 4' respectively, and the sills 9 and 10 comprise wooden upper portions 9' and 10' respectively, in order that wooden siding may be nailed thereto in case wooden upper framing and siding is desired. A suitable number of transverse tie-rods 11, 12, 13, 14, extend through the upper portions of the side sills and the center sills and also the intermediate sills for effectually preventing the side from being forced outwardly, the lower portions of the beams being prevented from spreading by means of the body-bolsters and preferably also by cross-tie beams 15 and 16.

The upper framing may suitably comprise corner posts 17, 18, 19, 20; door posts 21, 22, 23, 24; studding 25 and braces 26; plates 27 and 28; purlins 29 and roof 30. The framing comprises also a girth or belt rail 31 arranged at a suitable height. The doorways are provided with metallic door sills or threshold plates 32 and 33 provided at their inner edges respectively with lips 34 and 35 that extend upwardly and inwardly, the threshold plates being supported on wooden filling pieces 36 and 37 respectively that are arranged upon the side sills. Preferably two wooden nailing strips 38 and 39 are secured to the under sides of the side sills 3 and 4 respectively, two similar strips 40 and 41 being secured to the under sides of the end sills 9 and 10 respectively, a suitable siding 42 being secured to

the strips and also suitably secured to the upper portions of the framing. Inside lining 43 is secured to the posts and studding and extends up to the girth or belt rail, the latter preferably having a cap plate 44 thereon.

In accordance with the invention a metallic arch 45 is supported on the side sill 3 and on the intermediate sill 7, a similar arch 46 being supported on the side sill 4 and on the intermediate sill 8. A central arch 47 is supported on the center sills 5 and 6. An arch 48 is supported on the sills 5 and 7 and a similar arch 49 is supported on the sills 6 and 8. The arches preferably are composed of corrugated iron and rest upon the lower flanges of the sills and extend from one to the other one of the end sills 9 and 10. A suitable plastic composition is employed and placed upon the arches so as to constitute a foundation 50 which covers the upper portions of the center sills and intermediate sills, the foundation being deeper along the sides and ends 25 of the car than at the middle portion so that the water shall flow away from the sides and ends. The composition of the foundation should be such as to avoid excessive weight of material and preferably includes asbestos wool or mineral wool, and a suitable binder, such as cement. A side foundation 51 extends upward continuously from the floor foundation 50 and covers the inner face of the inside lining 43. A metallic floor 52 is placed upon the foundation 50 and is composed of woven wire, a metallic lining 53 extending from the floor 52 upward against the lining foundation 51 to the under side of the cap plate 44 and is secured 35 to the side foundation 51 and the inside lining 43 by means of staples 54 driven into the inside lining 43. A floor surface 55 is laid upon the reticulate metallic floor 52 and it is composed of suitable material that is 45 impervious to water, such as asphalt or asphalt composition of suitable consistency so that when applied the composition may be worked into the openings and under such of the wires as may not lie solidly upon the 50 foundation. The floor surface is graded in conformity to the floor foundation, and a trough 56 is formed in the floor midway between the planes of the two center sills and preferably extends from near one body-bolster nearly to the other body-bolster, the end portions of the floor surface sloping downwardly toward the ends of the trough, there being valleys 57 and 58 formed that extend from the two corners of one end of 55 the body to one end of the trough, and two other valleys 59 and 60 that extend from the corners of the opposite end of the car body to the opposite end of the trough. The floor surface at the inner sides of the 65 thresholds have slightly raised surfaces 61

and 62 that extend under the lips of the thresholds so as to more effectually prevent water from flowing out of the doorways when the car is canted over on curved tracks. Side surfacing 63 extends continuously from the floor surfacing 55 upward against the metallic side 53 to the under side of the plate 44 and is of suitable consistency to adhere to the metallic lining and also to the foundation 51.

It should be understood that the surfacing should be of such composition as to not be liable to become cracked but should be slightly elastic, the requisite firmness for preventing indentations being afforded by the wire netting embedded in the surfacing.

Two drain pipes 64 and 65 are provided and extend from opposite ends of the trough 56 down through the floor foundation 50 and the arch 47 without being secured to the foundation and the arch, each pipe having a flange 66 on its upper end that is embedded in the surfacing material and supports the pipe. The lower end of each drain pipe preferably has a cup-shaped trap 67 connected thereto which is adapted to permit water to pass out of the lower end of the pipe and flow over the top of the trap while preventing air from entering the drain pipe.

It should be understood that the upper portion of the car body may or may not be lined as may be desired, and in some cases may be equipped as heretofore for carrying the ice in the upper portion of the car body.

In practical use the different kinds of merchandise or material to be transported is placed upon the floor of the car, and when it is desired to keep the contents of the car at a relatively low temperature, it will be understood ice may be placed anywhere upon the floor or as in some cases in barrels or boxes with fish or perishable meats or vegetables, and as the ice melts and the resulting water escapes to the floor or in some cases against the inner side of the car, the water is conducted to the trough 56 and out through either one or both of the drain pipes in the floor and discharged onto the middle of the roadway unoffensively, while the car framing is effectually protected from the moisture.

Having thus described the invention, what is claimed as new is—

1. A car body including a plurality of horizontally arranged sills, upright side walls on the outermost ones of the sills, a floor foundation supported on and extending over the sills to the walls, the foundation having greater thickness adjacent to the walls than at a distance therefrom, linings formed integrally with the thicker portions of the floor foundation and extending upward against the walls, and staples se-

cured to the walls and the linings and embedded in the latter.

2. A car body including a plurality of horizontally arranged sills, end sills secured 5 to the plurality of sills, upright side walls on the end sills and outermost ones of the plurality of sills, a floor foundation supported on and extending over the sills to the walls, a lining foundation formed integrally 10 with the floor foundation adjacent the walls and extending upward against the walls, staples securing the lining foundation to the walls, and a surfacing layer extending unbrokenly over the floor foundation and 15 the lining foundation and intimately connected therewith, the layer extending over and covering the staples.

3. A car body including a plurality of parallel sills, a plurality of tie-rods extending 20 through the upper portions of all the sills and connected to the outermost ones thereof, a plurality of body-bolsters secured to the under sides of the sills, a plurality of arches supported by the sills and extending 25 above the body-bolsters and under the tie-rods, a floor foundation on the arches and extending over the intermediate ones of the sills, the foundation having a trough therein, elastic surfacing on the foundation,

and a drain pipe extending from the trough 30 through the foundation.

4. A car body comprising a plurality of horizontal longitudinal sills and end sills, upright side walls on the end sills and the outermost ones of the longitudinal sills, a 35 plurality of tie-rods extending through the upper portion of the longitudinal sills and connected to the outermost ones thereof, a plurality of body-bolsters secured to the under sides of the longitudinal sills, a plurality of arches supported by the longitudinal sills and extending above the body-bolsters and under the tie-rods, a floor supported on the arches and extending over 40 the intermediate ones of the longitudinal sills to the side walls and inclosing the tie-rods, the upper surface of the floor being concavely inclined, and two drain pipes connected to the central portion of the floor 45 in proximity to the body-bolsters respectively and extending through the floor and supporting arch thereof.

In testimony whereof, I affix my signature in presence of two witnesses.

AUGUST H. TOENS.
